UNITED STATES PATENT OFFICE.

BOONE U. TAYLOR, OF NASHVILLE, TENNESSEE, ASSIGNOR OF ONE-HALF TO JAMES H. CAMPBELL, CHARLES A. NELSON, HENRY C. MOORE, JR., AND AL D. MCKNIGHT, ALL OF MURFREESBORO, TENNESSEE.

ENGINE STARTER.

1,415,962.

Specification of Letters Patent. Patented May 16, 1922.

Application filed June 13, 1919. Serial No. 304,050.

To all whom it may concern:

Be it known that I, BOONE U. TAYLOR, a citizen of the United States, residing at Nashville, in the county of Davidson and

5 State of Tennessee, have invented certain new and useful Improvements in an Engine Starter, of which the following is a specification.

The invention relates to an internal combustion engine starting device, and more particularly to the class of acetylene generator attachments for internal combustion engines to be used as a starter therefor.

The primary object of the invention is the 10 provision of a device or attachment of this character wherein acetylene gas is generated and conveyed to the intake manifold of the internal combustion engine to assure the easy starting of the engine on the first turn 15 of its shaft in the hand cranking thereof, the device being of novel form so that the same can be mounted upon various types of internal combustion engines.

Another object of the invention is the provision of a device or attachment of this 20 character, wherein the requisite amount of acetylene gas will be generated for the successful starting of the internal combustion engine, without necessitating laborious hand cranking thereof, with resultant saving in the consumption of fuel, the device or attachment being easily manipulated to assure the initial starting charge for its introduction into the intake manifold of the motor, 25 whereby on the initial cranking thereof the charge will be drawn into the cylinders for the instant starting of the said motor.

A further object of the invention is the provision of a device or attachment of this 30 character, which is devoid of any complicated parts, thereby eliminating the necessity of repairs and assuring efficiency and positive operation.

A still further object of the invention is 35 the provision of a device or attachment of this character, which is extremely simple in construction, readily and easily attached to the motor, thoroughly reliable and efficient in its operation, strong, durable and inexpensive to manufacture and install.

With these and other objects in view, the invention consists in the features of construction, combination and arrangement of

parts as will be hereinafter fully described, illustrated in the accompanying drawing, 55 and pointed out in the claims hereunto appended.

In the accompanying drawing:—

Figure 1 is a fragmentary side elevation of an internal combustion engine, showing 60 the attachment constructed in accordance with the invention applied, showing by full lines one position of the attachment and by dotted lines another position thereof.

Figure 2 is a vertical longitudinal sectional view through the attachment or device.

Figure 3 is a view similar to Figure 1 showing the attachment in position for generating the starting charge.

Figure 4 is an elevation of a slight modification of the invention, showing by full lines the normal position of the carbide container and by dotted lines the adjusted position for the feeding of the carbide to the 75 water reservoir, a portion of the device or attachment being broken away.

Similar reference characters indicate corresponding parts throughout the several views in the drawing.

Referring to the drawing in detail, A designates generally an internal combustion engine, in this instance of the four cylinder type of any ordinary well known construction having the usual intake manifold. B, 80 while C is the starter device or attachment hereinafter fully described.

The starter device or attachment C comprises an acetylene generator including a water reservoir 5 and a superposed carbide 90 container 6 spaced a distance therefrom, the water reservoir being preferably made from glass, although the same may be made from metal or any other suitable material and has thereon a removable fluid tight cap 7, 95 so that the reservoir can be filled with water when the occasion requires.

The carbide container 6 is offset laterally with respect to the water reservoir 5 and passed upwardly through the bottom of said carbide container 6 is a rigid carbide feed tube 8 which is also passed through the cap 7 of the water reservoir and depends therein for a short distance, the tube 8 being integrally formed with the body of the carbide 100 container 6 and is adapted to deliver carbide 105

within the said container into the water reservoir 5 on the turning of the acetylene generator in a manner presently described.

The carbide container 6 at its top is formed with a filling spout 9 having a removable closure plug or stopper 10 of any desirable construction. The carbide is adapted to be introduced through the spout 9 into the carbide container 6 when it is desired to fill the same.

Formed near the upper end of the water reservoir 5 adjacent to the cap 7 thereon is an outlet nipple 11 to which is connected a flexible hose or tube 12, the same being also connected with a suitable coupling for joining the same to the intake manifold B of the engine A and this tube 12 serves to convey the acetylene gas generated to the intake manifold from the device or attachment to be drawn into the cylinders of the engine A, so that on the hand cranking of the said engine the same will be easily started. That is to say, when the shaft of the engine is first turned by the hand cranking thereof the motor will be instantly started.

Suitably mounted on the engine A or the truck frame of a motor vehicle carrying the same is a bracket 13 having a horizontally disposed pivot pintle 14 to which is pivotally connected at 15 for vertical swinging movement the acetylene generator. It is obvious that the generator can be turned on the pivot pintle 14 from normal vertical position to a substantially horizontal position by moving the said generator a quarter revolution.

In the use of the generator for starting purposes the water reservoir 5 is filled with water to a level in said reservoir at about two-thirds its height, the carbide container 6 being filled with carbide and on the turning of the generator from normal vertical position to substantially horizontal position the carbide contained in the carbide container 6 is gravitated and a portion thereof will enter the tube 8 and on reverting the generator or that is to say bringing the same in retrograde movement back to normal position the quantity of carbide within the tube 8 will precipitate into the water reservoir 5 and when contacting with the water therein acetylene gas will be generated above the water level and this gas will be conveyed through the flexible tube 12 into the intake manifold B of the engine A, so that on the cranking of the engine and the first turn of its shaft will effect the starting of the engine.

In Figure 4 there is shown a slight modification of the invention, wherein in substitute for the rigid feed tube 8 the water reservoir 16 is designed to be rigidly supported and is connected with the superposed offset carbide container 17 through the medium of a flexible tube 18, and this carbide con-

tainer 17 is adapted to be swung from vertical position to a substantially horizontal position for the supply of a quantity of carbide therein into the tube 18, whence the carbide in the tube will be delivered to the water reservoir 16 for the generation of gas above the water level therein. It will be apparent that the carbide container 17 can be moved independently while the water reservoir 16 is held in fixed relation thereto. It is to be understood that in lieu of the flexible tube 18 a break jointed connection can be had between the water reservoir 16 and the said carbide container 17 and this is contemplated within the scope of the invention, the water reservoir 16 being stationary supported in any suitable manner.

It will also be apparent that by reason of the offset relation of the water reservoir 5 relative to the carbide container 6 superposed therefrom on the turning of the acetylene generator the water container in the reservoir will not gain entrance through the tube 8 into the carbide container.

It is to be understood that changes, variations and modifications may be made in the invention such as come properly within the scope of the appended claims, without departing from the spirit of the invention or sacrificing any of its advantages.

From the foregoing it is thought that the construction and manner of operation of the device or attachment will be clearly understood and therefore a more extended explanation has been omitted.

What is claimed is:

1. The combination with an internal combustion engine including the intake manifold thereof, of a gas generator mounted on the frame of the engine, said gas generator comprising a water container, a carbide container rigidly connected to and in communication with said water container, means for delivering a charge of carbide to said water container, said charge delivery being effected by a reversed turning movement of said carbide and water containers, and means for conveying the gas generated in said water container to the manifold of the engine.

2. The combination with an internal combustion engine including the intake manifold thereof, of a supporting bracket on the frame of the engine, a gas generator carried by said supporting bracket, said gas generator comprising a water container, a carbide container rigidly connected to and in communication with said water container, means for delivering a charge of carbide to said water container, said charge delivery being effected by a reversed quarter turning movement of said carbide and water containers in said bracket, and means for conveying the gas generated in said water container to the manifold of the engine.

3. The combination with an internal combustion engine including the intake manifold thereof, of a supporting bracket on the frame of the engine, a gas generator carried by said supporting bracket, said gas generator comprising a water container, a carbide container in superposed relation with respect to said water container and rigidly connecting the same and in communication therewith, means for delivering a charge of carbide to said water container, said charge delivery being effected by a reversed quarter turning movement of said carbide and water containers in said bracket, and means for conveying the gas generated in said water container to the manifold of the engine.
4. The combination with an internal combustion engine including the intake manifold thereof, of a supporting bracket on the frame of the engine, a gas generator carried by said supporting bracket, said gas generator comprising a rigid feed tube extending vertically of said supporting bracket, a water container communicating with the lower end of said tube, a carbide container communicating with the upper end of said tube, means for delivering a charge of carbide to said water container, said charge delivery being effected by a quarter turning movement of said feed tube and said carbide and water containers carried thereby, and means for conveying the gas generated in said water container to the manifold of the engine.
5. The combination with an internal combustion engine including the intake manifold thereof, of a supporting bracket on the frame of the engine, a gas generator carried by said supporting bracket, said gas generator comprising a feed tube swivelled in said bracket for a quarter turn movement from its normally vertical position, a water container carried at the lower end of the tube and communicating therewith, a carbide container carried at the upper end of said tube and communicating therewith, the upper end of said tube being arranged with respect to the interior of the carbide container to receive a predetermined charge of the carbide when the tube of the containers is moved to horizontal position and to deliver the same to the water container when moved back to vertical or normal position, and a connection between the generator and the engine manifold for conveying the gas generated in water container to the latter.
6. In an engine starter, the combination with an internal combustion engine including the intake manifold thereof, of a gas generator adapted to be mounted on the engine and comprising a water container, a carbide container in superposed relation with respect to said water container and hav-

ing overlapping communication therewith, means for measuring charges of the carbide when the generator is turned from its normal vertical position to a horizontal position, said means acting to deliver the measured charge to said water container when the generator is returned to normal position, and means for conveying the generated gas from said water container to the intake manifold of the engine.

7. In an engine starter, the combination with an internal combustion engine including the intake manifold thereof, of a gas generator adapted to be mounted on the engine and comprising a water container, a carbide container in superposed relation with respect to said water container, a rigid tube connection extending between said water container and said carbide container and adapted for communication therebetween, the end of said tube extending within said carbide container being so formed and arranged with respect to the opposed wall of the container as to provide a charge measuring means for the carbide when the generator is turned from normally vertical position to the horizontal, the charge of carbide being delivered by gravity through said tube to said water container when the generator is returned to normal vertical position, and means for conveying the generated gas from said water container to the intake manifold of the engine.

8. In an engine starter, the combination with an internal combustion engine including the intake manifold thereof, of a gas generator adapted to be mounted on the engine and comprising a water container, and carbide container in superposed relation with respect to said water container, a supporting bracket for the gas generator, a rigid tube connection extending between said water container and said carbide container and adapted for communication therebetween, said tube being swivelled in said supporting bracket whereby the generator is adapted to be turned from normally vertical position to bring the same into horizontal position, the end of said tube extending within said carbide container being so formed and arranged with respect to the opposed wall of the container as to provide a charge measuring means for the carbide so that, when the generator is turned back to its normally vertical position from the horizontal, the charge of carbide will be delivered by gravity through said tube to said water container, and means for conveying the generated gas from said water container to the intake manifold of the engine.

In testimony whereof, I affix my signature hereto.

BOONE U. TAYLOR.
